A. J. FRAME

DISPENSING DEVICE

Filed May 19, 1921

A. J. Frame Inventor

Ogle R. Singleton.
Attorney

UNITED STATES PATENT OFFICE.

ARCHIE JAMES FRAME, OF MIAMI, FLORIDA, ASSIGNOR OF ONE-HALF TO FRANK L. FELIX, OF HARTFORD, KENTUCKY.

DISPENSING DEVICE.

Application filed May 19, 1921. Serial No. 470,974.

To all whom it may concern:

Be it known that I, ARCHIE JAMES FRAME, a citizen of the United States, residing at Miami, in the county of Dade and State of Florida, have invented certain new and useful Improvements in Dispensing Devices, of which the following is a specification.

My invention consists in a new and useful improvement in dispensing devices, and is 10 designed more particularly for use in connection with oil cans and similar forms of lubricant receptacles.

The purpose of my invention is to provide a force-feed oil can having a pump cylinder 15 which is provided with slide valves. Valves of this type are superior to valves of the seating type, such as disc or ball valves, for the reason that slide valves are reliable in opening and closing the ports of the pump 20 cylinder, since they cannot be clogged by grit or lint in the lubricant passing through them. Such foreign substances, often present in the lubricant, tend to obstruct valves of the seating type, and thus prevent the 25 effective operation of the forced feed.

The novel feature of my invention consists in the use in the pump cylinder of two slide valves to control the inlet and outlet ports of the cylinder, respectively. By the 30 use of my novel construction it is possible to produce a force-feed oil can in which a column of oil may be supplied to the spout of the can and retained therein by the closing of the outlet valve in the pump cylinder 35 during each successive suction stroke of the piston. This is a very important advantage in a device of this kind as it makes it possible to supply a lubricant to otherwise inaccessible points at considerable heights above 40 the dispensing device.

My invention is embodied in the details of construction illustrated in the drawing and hereinafter fully described, but I do not consider my invention limited to the specific 45 embodiment shown herein but refer for its scope to the claim appended hereto.

The drawing is a side elevation of an oil can embodying my invention, portions of the wall of the can being broken away to 50 expose the operative mechanism which is shown in section.

The oil can O is of the ordinary type, provided with the usual cap O¹ covering the opening in the can O through which the oil 55 may be supplied to the can O. In the can O,

there is disposed the pump cylinder C which protrudes through the rear wall of the can O above the handle H. Near its lower end the cylinder C is provided with two ports C¹ and C². Connected with the port C¹ is a 60 short pipe I extending downwardly from the cylinder C to a point closely adjacent the bottom of the can O. Connected with the port C² is the pipe J which extends upwardly from the cylinder C and connects 65 with the spout R of the can O. This spout R is not in communication with the interior of the can O except through the pump cylinder C. The end of the cylinder C outside 70 of the can O is closed by a screw-cap C³ and the cylinder C is closed at its end within the can O by an end wall C⁴. Through the center of the screw-cap C³ there is slidably disposed the piston P having upon its end within the cylinder C the head P¹ upon which is 75 mounted the cup-washer P² by means of the washer P³ and the nut P⁴. This cup-washer P² fits snugly inside of the sleeve S which is slidably disposed within the cylinder C. Between the piston P and the wall C⁴ there 80 is disposed the coil spring P⁵ adapted to hold the piston P normally at the upper end of the cylinder C. A thumb button P⁶ is provided upon the outer end of the piston P.

The sleeve S is made somewhat shorter 85 than the inside length of the cylinder C so that the sleeve is permitted endwise movement in the cylinder. The sleeve S is provided with two ports S¹ and S², which are so disposed relative to the ports C¹ and C² 90 that when the sleeve S is moved to its limit of movement in one direction the ports S¹ and C¹ register, and when it is moved to the limit of its movement in the opposite direction the ports S² and C² register. 95

The handle H has its lower end H¹ fastened to the can O near its bottom and its upper end H² fastened to the can O directly under the cylinder C. A pin H³ passes through the end H² and the cylinder C at this point and is received through a slot S³ in the sleeve S. This pin H³ and slot S³ serve to hold the sleeve S in such position relative to the cylinder C that the ports C¹ and S¹ and the ports C² and S² will be kept 100 in constant alignment.

From the foregoing description it will be obvious that as the spring P⁵ presses the piston P outwardly the contact of the washer P² will move the sleeve S until its upper end 110

strikes the cap C³. When the sleeve S assumes this position the ports S¹ and C¹ register and the sleeve S closes the port C². When the ports are in this position the oil 5 within the can O flows through the intake pipe I, and the ports C¹ and S¹ to fill the interior of the pump cylinder C. When the piston P is forced into the cylinder C by 10 pressure of the thumb of the user upon the button P⁶, the washer P² causes the sleeve S to move downwardly until its lower end strikes the end wall C⁴ of the cylinder C. When the sleeve S assumes this position, the 15 sleeve S closes the intake port C¹ and the ports C² and S² register, thus opening the outlet for the oil into the pipe J. The pressure exerted upon the oil in the cylinder C by the piston P causes it to flow from the cylinder through the ports C² and S², and 20 the pipe J to the spout R, and thus be dispensed as desired. When pressure upon the piston P is removed, the spring P⁵ retracts the piston P in the cylinder C, thus restoring the sleeve S to its initial position and 25 thus closing the outlet port C² and again opening the inlet port C¹. The retraction of the piston P causes oil to flow through the pipe I and ports C¹ and S¹ and thus refill the cylinder C with a new charge. 30 The closing of the port C² holds the column of oil supplied to the pipe J and spout R therein, and when the operation of the piston P is repeated the next charge forces outwardly the oil contained in the pipe J and 35 spout R. Thus it will be seen that so long

as the supply of oil in the can O is adequate, the mechanism will continue to lift the column of oil in the pipe J and spout R, thus making it possible to pump oil through a considerable length of spout to reach an 40 otherwise inaccessible height.

Having described my invention, what I claim is:

In a force-feed oil can, the combination of an oil reservoir; a chamber provided with 45 an inlet port and an outlet port; an inlet pipe connecting said inlet port with the interior of the reservoir; a discharge pipe connecting with said outlet port; a reciprocable sleeve in said chamber provided with an 50 inlet port and an outlet port; a pin-and-slot connection between said chamber and said sleeve adapted to maintain said chamber ports and said sleeve ports in constant alignment; a piston head movable in said sleeve; 55 said sleeve and said piston head being so related to each other and to said chamber that when said piston head is moved on the intake stroke said sleeve intake port and said chamber intake port are moved into 60 register, suction being effected through said inlet pipe, and when said piston head is moved on the discharge stroke said sleeve outlet port and said chamber outlet port are moved into register, compression being 65 effected through said outlet pipe; and a manually operated piston rod adapted to move said piston head.

In testimony whereof I affix my signature.

ARCHIE JAMES FRAME.
